UNITED STATES PATENT OFFICE.

ALEX VAJDA, OF NORTH CHICAGO, ILLINOIS.

DESIGN FOR A CAMP-TABLE.

50,670.

Specification for Design.

Patented Apr. 24, 1917.

Application filed December 27, 1916. Serial No. 139,218. Term of patent 7 years.

To all whom it may concern:

Be it known that I, ALEX VAJDA, a subject of the King of Hungary, residing at North Chicago, in the county of Cook and State of Illinois, have invented a new, original, and ornamental Design for a Camp-Table, of which the following is a specification, reference being had to the accompanying drawing, forming part thereof.

The figure is a view in perspective of a camp table, showing my new design.

I claim:—

The ornamental design for a camp table, as shown.

ALEX VAJDA.

Witnesses:

HUGO RICHOEIR,
LAUSEAR REPAS.
